Primary Examiner—Dominic Simone*Attorney, Agent, or Firm*—Laff, Whitesel, Conte & Saret, Ltd.**[57] CLAIM**

The ornamental design for an antenna assembly with radome, as shown and described.

DESCRIPTION

FIG. 1 is a front perspective view of an antenna assembly with radome, showing my new design;

FIG. 2 is a front plan view of FIG. 1;

FIG. 3 is a side elevational view of FIG. 1, the other side being a mirror image thereof;

FIG. 4 is an end elevational view of FIG. 1, the other end being a mirror image thereof; and,

FIG. 5 is a back elevational view of FIG. 1.

The broken line disclosure in FIGS. 4 and 5 is for illustrative purpose only and forms no part of the claim.
